CHEMICAL COMPOSITION

Robert N. MacDonald, Wilmington, Del., assignor,
by mesne assignments, to the United States of
America as represented by the Secretary of War

No Drawing. Application December 11, 1945,
Serial No. 634,409.

2 Claims. (Cl. 252—187)

1

This invention relates to bleaching compositions and more particularly to a bleach solution which will adhere to surfaces to increase the time of contact of the surface with the bleach.

An object of this invention is to produce an adherent bleach composition which is economical and which will adhere to vertical and slanting surfaces.

A further object of this invention is to develop a bleach slurry which will effectively decontaminate surfaces which have been exposed to the action of vesicant agents.

My composition has been developed to treat surfaces which have been exposed to the action of vesicant agents such as mustard gas ($\text{C}_1\text{H}_2\text{CH}_2\text{SCH}_2\text{CH}_2\text{Cl}$) to decontaminate said surfaces in order that personnel may exist in the contaminated area without wearing protective clothing. The composition, however, can also be used for bleaching vertical surfaces since the bleach:water slurry is very adherent and will expose the surfaces to the action of the bleach for a comparatively long period of time. My bleach slurry does not run off of said surfaces, its action is therefore, intensified and more effective results are obtained.

It has been known in the past to thicken bleach solutions by the addition of such compounds as fuller's earth, Iceland and Irish moss, kieselguhr, diatomaceous earth, glutinative substances and colloidal compositions obtained from bentonite. However, the addition of these substances, usually in very large proportion, to bleach solutions has been performed with the object of making the bleach solution nearly dry, absorbent to oily matter, and to dilute the action of the bleach to obtain less destruction of the material to be treated.

The object of my invention is entirely different. Asbestos is added to the bleach solution in very small proportion in order to render the bleach water slurry more adherent and to extend the time of action of the bleach composition on vertical and slanted surfaces. Furthermore, in the preferred embodiment of my invention, the adherent bleach:water slurry is to be used to decontaminate surfaces exposed to vesicant agents.

I have discovered that the addition to conventional bleach slurries of a small amount of asbestos fiber produces an adherent suspension which increases the effectiveness of the slurry when applied to slanting and vertical surfaces. In order to increase the action of my composition, a minor amount of a wetting agent can be added. Any wetting agent which does not react with the bleaching powder may be employed.

2

Since concentrated bleach slurries have a tendency to gel, an anti-setting or anti-gelling agent may be added.

I have found that the adherence per unit area of bleach:water slurries to vertical surfaces and hence, their bleaching and decontaminating efficiency, is greatly increased by the addition of a small amount of finely divided asbestos fiber. For example, the adherence per unit area to a vertical surface of a 40:60 bleach:water slurry is approximately doubled by the incorporation of 0.25% of "Mikro-pulverized" asbestos fiber and is almost quadrupled by the incorporation of 0.75% of the same fiber. An asbestos thickened 15 40:60 bleach:water slurry has an adherence to vertical surfaces which is equal to or greater than that exhibited by a 50:50 bleach:water slurry. The 50:50 bleach:water slurry however, is not only more wasteful in the use of bleach, but also is much more difficult to handle.

The preferred embodiment of my invention is illustrated by the following example.

Example.—A bleach:water slurry is prepared by adding 1250 parts of bleaching powder (chloride of lime containing 35% available chlorine) to a solution of 6.3 parts of sugar in 1870 parts of water, the sugar serving to prevent setting, or gelling, of the slurry. After agitating the mixture vigorously for 15 to 20 minutes, 3.1 parts of finely divided asbestos powder (Canadian Government specification 5-K, grade 0-0-12-4, which has been "Mikro-pulverized" and has a maximum fiber length of 400 microns with 93% having a fiber length less than 100 microns), and 0.31 part of sodium dodecyl sulfate are added and mixing continued until a uniform slurry is obtained, this usually requiring only 5 to 10 minutes. The mixture is then strained through a screen having openings $\frac{3}{32}$ " in diameter and sprayed onto a vertical glass plate. After allowing the excess paste to drain from its surface, the plate is weighed. On the basis of the weight of the moist film and the proportion of dry bleach in the original slurry, the amount of dry bleaching powder adhering to a unit area of the vertical plate is calculated to be 6.6 oz./sq. yd. A film of bleach applied in the same manner from a control composition containing no asbestos thickener amounts to only 2.7 oz./sq. yd.

Any type of asbestos fiber which has a particle size approaching that given in the example can be used in my invention. Asbestos fiber according to Canadian specifications 5-K, grade 0-0-12-4, contain fibers of a size suitable for use in bleach water slurries to be sprayed from small

scale apparatus, but the fibers are too large for use in slurries to be sprayed from large scale apparatus. For use in large sprayers such as those of 400-gallon capacity, the asbestos fiber should be reduced to a maximum length of 400 microns to prevent clogging the filters in the spray apparatus. Satisfactory particle size can be obtained by subjecting commercial fiber to disintegration in a "Mikro-pulverizer" (a machine which is obtainable in the commercial market).

The proportion of asbestos fiber to be incorporated in the bleach: water slurry is not fixed but should be small (roughly on the order of $\frac{1}{4}$ to 5%). This proportion depends on several factors such as, for example, the concentration of the slurry, the degree of thickening desired and the particle size of the asbestos. By way of illustration, 0.25% of the "Mikro-pulverized" asbestos of the example is about as effective as 0.75% of grade 0-0-12-4 asbestos.

Instead of sodium dodecyl sulfate, any wetting agent can be employed in minor amounts if it is not reactive with the bleaching powder used.

Sugar can be replaced by any of the known anti-setting or anti-gelling agents.

The nature of this invention has been broadly outlined above, the preferred embodiments have been described and it will be apparent that certain modifications and additional formulations will suggest themselves to those skilled in the art. Accordingly, it is intended that the foregoing de-

scription shall be interpreted as illustrative only and not in a limiting sense.

I claim:

5 1. A decontaminant for vesicant gases consisting of approximately 1250 parts of bleaching powder having 35% available chlorine, 6.3 parts of sugar, 3.1 parts of comminuted asbestos powder having a maximum fiber length of 400 microns, .31 part of sodium dodecyl sulfate and

10 1870 parts of water.

15 2. A decontaminant for vesicant gases consisting of, from 3.1 to 155 parts of asbestos, 1250 parts of bleaching powder having approximately 75% of available chlorine, 6.3 parts of sugar, .31 part of sodium dodecyl sulfate, and 1870 of water.

ROBERT N. MACDONALD.
